UNITED STATES PATENT OFFICE.

PETER WEBER, OF ORANGE, NEW JERSEY.

SUPPORT FOR SHAFT-HANGERS.

No. 853,662.

Specification of Letters Patent.

Patented May 14, 1907.

Application filed March 1, 1907. Serial No. 360,081.

To all whom it may concern:

Be it known that I, PETER WEBER, a citizen of the United States, and a resident of Orange, in the county of Essex and State of New Jersey, have invented certain new and useful Improvements in Supports for Shaft-Hangers, of which the following is a description.

My invention relates to improvements in supports for shaft hangers adapted for use in modern concrete buildings.

In the construction of concrete buildings each ceiling presents a series of reinforced concrete beams supporting the floor above or the roof, as the case may be, and heretofore great difficulty has been experienced in properly supporting shaft hangers from these beams. In doing this work it has been usually the custom to drill through the beams so as to obtain a firm support therefrom and from these supports the shaft hangers are carried in various ways. The work, however, is tedious and expensive, the result is frequently unsightly, and it is difficult to obtain proper alinement.

The object of my invention is to provide an improved support for shaft hangers of a superior character in which great strength will be secured, a neat and attractive appearance obtained and perfect alinement of the shaft or shafts permitted.

In order that the invention may be better understood, attention is directed to the accompanying drawing in which—

Figure 1, is a sectional view through a concrete beam illustrating supports for two lines of shaft hangers; Fig. 2, a sectional view on the line 2—2 of Fig. 1; Fig. 3, an end view, partly in section, showing the supports and illustrating a single hanger in position, and Fig. 4, a section on the line 4—4 of Fig. 3, looking downward.

In all of the above views corresponding parts are represented by the same reference numerals.

1 represents the concrete beam, preferably reinforced in the usual way and within which are embedded during the molding thereof, two or more bolts 2—2. Preferably these bolts are surrounded by tubes 3 whose exterior may, if desired, be roughened so as to increase the contact with the cement and which tubes support the bolts by means of washers 4 placed between the upper ends of the tubes and the heads of the bolts. To

those skilled in the art of making concrete buildings it will be understood that the bolts 2, tubes 3 and washers 4 will be properly supported in the usual molds before the concrete is introduced therein, so that when the concrete is set the bolts will be very firmly supported and sustained within the beams. Carried by the bolts 2—2 are plates 5 having slots 6 so as to permit the plates to be properly lined up as will be understood. The plates 5 are formed with lugs 7 through which extend the pipes 8 which latter are preferably ordinary gas pipes. Preferably three lines of pipes are used so as to support two separate lines of shaft hangers as will be understood. When a single line of shaft hangers is to be supported, two lines of pipes will be employed. The pipes 8—8 are preferably secured in the lugs 7 by means of set screws 9. Carried by the pipes 8—8 are the supporting plates 10 each of which is formed preferably with a pair of hooks 11 at one end, which extend over the outside pipes 8, and with a pair of eyes 12 at the other end, engaging the middle line of pipe. In setting up the supports 10 it will only be necessary to thread the middle line of pipe through the eyes 12 of a series of supports, since the hooks 11 can be placed over the outer line of pipes without removing the latter. After the supports 10 have been mounted in place, the shaft hangers 13 which are of any suitable type, are secured thereto by means of bolts 14, working preferably in slots 15 in the supports so as to permit adjustment of the hangers. To prevent dislodgment lengthwise of the supporting pipes, the supports 10 may be provided with one or more set screws 16 passing through the eyes 12 and engaging the pipe 8 therein.

Having now described my invention, what I claim as new and desire to secure by Letters Patent, is as follows:

1. The combination with a concrete beam, of supporting bolts molded therein and extending beneath the same, a plate carried by said bolts at the bottom of the beam, a series of longitudinal supports carried by said plates and a shaft hanger carried by the longitudinal supports, substantially as set forth.
2. The combination with a concrete beam, of tubes molded therein, supporting bolts carried by said tubes and extending beneath the beam, a plate carried by said bolts at the bottom of the beam, a series of longitudinal

supports carried by said plates and a shaft hanger carried by the longitudinal supports, substantially as set forth.

3. The combination with a concrete beam, 5 of tubes molded therein, supporting bolts carried by said tubes and extending beneath the beam, a washer arranged between the upper end of each tube and the head of the bolt within the same, a plate carried by said bolts at the bottom of the beam, a series of longitudinal supports carried by said plates and a shaft hanger carried by the longitudinal supports, substantially as set forth.

4. The combination with a concrete beam, 15 of supporting bolts molded therein and extending beneath the same, a plate adjustably carried by the said bolts at the bottom of the beam, a series of longitudinal supports carried by said plates and a shaft hanger carried 20 by the longitudinal supports, substantially as set forth.

5. The combination with a concrete beam, 25 of supporting bolts molded therein and extending beneath the same, a plate carried by said bolts at the bottom of the beam, a series of longitudinal supports carried by said plates, a hanger support carried by the longitudinal supports, and a shaft hanger carried 30 by the hanger support, substantially as set forth.

6. The combination with a concrete beam, 35 of supporting bolts molded therein and extending beneath the same, a plate carried by said bolts at the bottom of the beam, a series of longitudinal supports carried by said

plates, a hanger support carried by the longitudinal supports, and a shaft hanger carried by the hanger support and adjustable thereon, substantially as set forth.

7. The combination with a concrete beam, 40 of supporting bolts molded therein and extending beneath the same, a plate carried by said bolts at the bottom of the beam, a series of longitudinal supports carried by said plates, a hanger support hooked at one end 45 over one of the longitudinal supports and threaded at the other end of an adjacent longitudinal support, and a shaft hanger carried by the hanger support, substantially as set forth.

8. The combination with a concrete beam, 50 of supporting bolts molded therein and extending beneath the same, a plate carried by said bolts at the bottom of the beam, three parallel lines of longitudinal supports carried 55 by said plates, a hanger support carried by the middle longitudinal support and one of the outside longitudinal supports, and a second hanger support carried by the middle longitudinal support and the other outside 60 longitudinal support, and hanger supports offering support for shaft hangers, substantially as set forth.

This specification signed and witnessed this 27th day of February 1907.

PETER WEBER.
